Primary Examiner — Susan Moon Lee(74) *Attorney, Agent, or Firm* — Lewis Roca Rothgerber LLP; Samantha A. Updegraff(57) **CLAIM**

I claim the ornamental design for a bird feeder, as shown and described.

DESCRIPTION

FIG. 1 is a perspective view of a bird feeder showing my new design;

FIG. 2 is a front view of a bird feeder;

FIG. 3 is a back view of a bird feeder;

FIG. 4 is a right side view of a bird feeder;

FIG. 5 is a left side view of a bird feeder;

FIG. 6 is a top view of a bird feeder; and,

FIG. 7 is a bottom view of a bird feeder.

The appearance of the central stand unit as visible in FIG. 1, upon which the disclaimed sphere is directly resting upon, is substantially the same in the other three sides. The rainbow-shaped upper line framing running along the openings of this central stand unit, as depicted in FIG. 1, is flat or two-dimensional. Any portions of the invention which are not visible, form no part of the claimed design.

Broken lines and unshaded portions contained within broken lines are not claimed.
